SIDE BEARING

Emil H. Blattner, Rochester, N. Y., assignor to
 The Symington-Gould Corporation, Depew,
 N. Y., a corporation of Maryland

Application June 19, 1948, Serial No. 33,964

10 Claims. (Cl. 308—138)

1

This invention pertains to a side bearing and more particularly to a yieldable or resilient type thereof.

An object of this invention is the provision, in an improved side bearing, of an arrangement of yieldable elements capable of functioning as resilient means to allow a compressive action of the side bearing and further to urge one part of the side bearing into frictional engagement with another part thereof.

A further object of the invention is the provision, in an improved side bearing, of an arrangement whereby frictional forces created during a compressive movement of the side bearing are greater than during a release action or movement thereof.

The above and numerous other objects of this invention will become apparent from the succeeding description considered together with the accompanying drawing wherein:

Figure 1 is a partial plan and partial horizontal sectional view of a side bearing embodying the present invention.

Figure 2 is a vertical sectional view taken along the lines 2—2 of Figure 1, looking in the direction of the arrows.

Figure 3 is a vertical sectional view taken along the lines 3—3 of Figure 2, looking in the direction of the arrows.

Referring now in detail to the drawing, wherein like reference characters indicate like parts, the numeral 1 is employed to designate, in a somewhat general manner, a side bearing exemplary of the present invention. This side bearing is arranged to be disposed between a railway truck bolster characterized by the surface 2 and a body bolster or body side bearing characterized by the surface 3 in Figure 2 of the drawing only. More specifically the side bearing has, as a component thereof, a housing or casing 4 having a base or bottom plate 5 arranged to bear upon a truck bolster adjacent each end thereof. The base plate is provided with suitable apertures 6 which function as accommodations for rivets (not shown) with the latter removably securing the housing to the bolster. While the housing may form an integral part of the bolster to be cast therewith it is, however, preferred at the present writing, to form it as a separate element and removably secure it to the bolster. Also, as will be clearly understood, a side bearing is disposed adjacent each end of the truck bolster and functions as a means whereby a rocking or rolling action of a car body (not shown) will be limited. Toward the completion of the housing there up-

2

stands from the base plate, a plurality of walls of substantially the same height characterized by end walls 7 and side walls 8 all joined together at their ends to define a cavity 9 therebetween.

5 Poised above the upper limits of the housing walls is a top or cover plate 10 of such horizontal extent as to overlie and be in position to engage the side walls. A cap or shoe 11 of hollow cast construction is supported by the top plate and has an upward facing surface 12 arranged to bear against and frictionally engage the surface 3 so that as the railway truck pivots, during service, beneath the car body the frictional forces created by the engaging surfaces 12 and 3 moving relative to one another will function as a retarding element to thus control such pivotal truck movement. The cap comprises a top wall 13 which carries the upwardly facing previously mentioned surface 12 and adjacent to the extremities of this top wall there depends therefrom end flanges 14 and side flanges 15 joined together to present a continuous structure. The flanges overlap the housing walls in outwardly telescoped relation thereto and as such, among other features, form 15 a skirt or shield to prevent the entrance of any foreign substance to the interior of the housing. It is found, almost without exception, that after body and truck bolsters are mated the vertical distance between the surfaces 2 and 3 is not equal to the predetermined calculated distance for this space. This is true whether the bolsters are of cast, fabricated or composite form. It, therefore, is necessary to make provisions in or about the side bearing so as to compensate for manufacturing tolerances. Such provisions are characterized by the introduction of shims 16 between the top plate and cap and while a specific number of shims are illustrated it will be clearly understood that any number of shims may be employed 20 and of any thickness since no two cases may be found identical. The presence and characteristics of the shims will be dependent upon the particular condition existing at the space where a side bearing is to be applied or introduced.

25 30 35 40 45 50 55

The side bearing under consideration is of the yieldable type so that it will function as a cushioning means to resist yieldably or control a rocking or rolling action of the car body. The compressive movement of the side bearing should of course be limited so that after the car body has rolled to one side or the other through its permissible degree, the side bearing will then act as a solid column to stop any further or continued movement in the same direction. As previously set forth the top plate is poised above the housing

and the distance between cap and subjacent housing is determinative of the permissible compressive movement of the side bearing. It will therefore be clearly understood that the distance between the cap and housing is predetermined and if after a side bearing has been placed between opposing surfaces 2 and 3 it is found that this distance is other than that predetermined then the addition or removal of shims will establish a proper distance between the top plate and housing. Also the top plate completely overlies the housing walls so that after the side bearing has been fully compressed the top plate will bear upon the housing and the side bearing will then function as a solid, rigid column until released of its superimposed load to allow an expansive movement of the bearing. After a bearing is assembled and applied the distance between the top plate and housing should be gauged to make sure it is equal to that distance predetermined or permitted. For this purpose, therefore, each cap end flange is provided with an opening 17 which exposes the critical area and through which a gauge or any other proper implement may be inserted.

Often, heretofore, reference has been made to the yieldable characteristics of the side bearing. Toward the fulfillment of this feature the housing is provided with spring seats 18, preferably a pair thereof spaced from one another longitudinally of the side bearing and formed on the base plate. Related with the housing spring seats is a pair of spring seats 19 formed on the top plate and facing downwardly toward their companion upwardly facing housing spring seats. Disposed between and reacting between the spring seats of the housing and top plate, are yieldable or resilient means which may be of any type or nature but herein are characterized by double coil springs 20. The coil springs, of a free height greater than the height illustrated in the drawing are, assembled in the side bearing, under an initial compression and accordingly any movement of the surfaces 2 and 3 toward one another will be cushioned by a further compressive action of the coil springs.

In order to augment the value of the coil springs and further to snub any harmonic action of the coil springs the components of the side bearing are arranged for the creation of frictional forces. Toward the accomplishment of the above the spring seats are tilted or inclined relative to a horizontal plane to form an oblique angle therewith. Since the spring seats are tilted the coil springs are also tilted at an angle normal to the spring seats and thereby a flat bearing engagement will be present between the coil springs and their seats. The coil springs lean toward a housing end wall 1a and away from a housing end wall 1b and, therefore, what might be considered as a leading edge 21 of the top plate is at all times urged into intimate contact with the cap end flange 14a to urge the cap, at all times, in one direction only. This spring action will also pull the cap end flange 14b into intimate contact with the housing end wall 1b so as to be in frictional engagement therewith. The capacity of the side bearing is further increased by forming at least the end wall 1b and end flange 14b as tapered elements so that their greatest thicknesses are adjacent their bases. As will be noted, any compressive movement taking place in the side bearing will result in the development of an increase in the frictional resistance offered. It is also to be here noted that the inclination of

the springs is such that the transverse component will create pressure on the walls 1b and 14b in excess to the frictional resistance between the cap surface 12 and the body surface 3 so that as the truck which carries this side bearing executes a curve in the tracks the cap wall 14b will not be moved away from the housing wall 1b.

From the above it will be noted that various changes and alterations may be made to the structure of the accompanying drawing and the herein contained description thereof without departing from the spirit of this invention and scope of the appended claims.

I claim:

1. In a side bearing, the combination of, a housing having a base with tilted spring seats, a cap in overlapping relation with said housing and having tilted spring seats associated therewith, and spring means interposed between and bearing against said spring seats; said spring means being tilted so as to allow said cap to move vertically and to urge said cap horizontally into frictional engagement with said housing.

2. In a side bearing, the combination of, a housing having a base with tilted spring seats, a top plate having tilted spring seats, a cap in overlapping relation with said housing and carried by said top plate, and spring means interposed between and bearing against said spring seats; said spring means being tilted so as to allow said cap to move vertically and to urge said cap into frictional contact with said housing.

3. In a side bearing, the combination of, a housing having a base with tilted spring seats, a top plate having tilted spring seats parallel with said housing spring seats, a cap supported by said top plate and in outer telescoping relation with said housing, and coil spring means interposed between and bearing against said spring seats; said coil spring means being tilted so as to allow said cap to move vertically and to urge said cap in one direction into frictional contact with said housing.

4. In a side bearing, the combination of, a housing having a base with tilted spring seats, a top plate having tilted spring seats parallel with said housing spring seats, a cap supported by said top plate and in outer telescoping relation with said housing, and coil spring means interposed between and bearing against said spring seats; said coil spring means being tilted so as to allow said cap to move vertically and to urge said cap in one direction into frictional contact with said housing; contacting surfaces of said cap and housing being inclined so as to increase frictional resistance therebetween as the cap moves downwardly.

5. In a side bearing, the combination of, a housing having a base with tilted spring seats, a top plate having tilted spring seats parallel with said housing spring seats, a cap supported by said top plate and in outer telescoping relation with said housing, a shim interposed between said top plate and cap, and coil spring means interposed between and bearing against said spring seats; said coil spring means being tilted so as to allow said cap to move vertically and to urge said cap in one direction into frictional contact with said housing.

6. In a side bearing, the combination of, a housing having a base with tilted spring seats, a top plate normally spaced above and spanning said housing, tilted spring seats on said top plate, a cap outwardly telescoping said housing and supported by said top plate, and coil springs react-

ing against said spring seats, said coil springs being tilted and urging said cap through said top plate into frictional engagement with said housing.

7. In a side bearing, the combination of, a housing having a base, a plurality of spring seats facing in the same direction and inclined toward an end of said housing, a top plate spaced above said housing by an amount to determine the permissive movement of said top plate, a plurality of tilted spring seats on said top plate and facing said first named spring seats, a cap supported by said top plate, and coil springs acting between said spring seats; said coil springs being tilted and urging said top plate against said cap and said cap against said housing.

8. In a side bearing, the combination of, a housing having a base, a plurality of spring seats facing in the same direction and inclined toward an end of said housing, a top plate spaced above said housing by an amount to determine the permissive movement of said top plate, a plurality of tilted spring seats on said top plate and facing said first named spring seats, a cap supported by said top plate, coil springs acting between said spring seats; said coil springs being tilted and urging said top plate against said cap and said cap against said housing; and a shim interposed between said cap and top plate.

9. In a side bearing, the combination of, a housing having a base, a plurality of spring seats facing in the same direction and inclined toward an end of said housing, a top plate spaced above said housing determinative of a compressive movement of said side bearing, said top plate having a plurality of spring seats facing in the same di-

rection and inclined toward another end of said housing, a cap supported by said top plate and telescoping said housing, and spring means acting between said spring seats; said spring means being tilted and urging said top plate against said cap and said cap in one direction only into frictional engagement with said housing.

10. In a side bearing, the combination of, a housing having a base, a plurality of spring seats facing in the same direction and inclined toward an end of said housing, a top plate spaced above said housing determinative of a compressive movement of said side bearing, said top plate having a plurality of spring seats facing in the same direction and inclined toward another end of said housing, a cap supported by said top plate and telescoping said housing, and spring means acting between said spring seats; said spring means being tilted and urging said top plate against said cap and said cap in one direction only into frictional engagement with said housing; said cap and housing being so arranged and constructed that frictional resistance is greater during a compressive action of said side bearing.
